UNITED STATES PATENT OFFICE

169,253

BOTTLE OPENING AND RESEALING TOOL

Norman A. Hagedorn, Middletown, Ohio

Application December 23, 1952, Serial No. 22,841

Term of patent 14 years

(Cl. D44—29)

To all whom it may concern:

Be it known that I, Norman A. Hagedorn, a citizen of the United States, residing in the city of Middletown, county of Butler, State of Ohio, have invented a new, original, and ornamental Design for a Bottle Opening and Resealing Tool, of which the following is a specification, reference being had to the accompanying drawing, forming a part thereof, in which

Fig. 1 is a perspective view of the tool embodying my new design, viewed from one end thereof; and

Fig. 2 is a perspective view of the tool as viewed from the opposite end and obverse side.

I claim:

The ornamental design for a bottle opening and resealing tool, as shown.

NORMAN A. HAGEDORN.
